Patented June 29, 1915.

UNITED STATES PATENT OFFICE.

FRANCIS MEISEL, OF BOSTON, MASSACHUSETTS, ASSIGNOR TO MEISEL PRESS & MANUFACTURING COMPANY, OF BOSTON, MASSACHUSETTS, A CORPORATION OF MASSACHUSETTS.

PRINTING-MACHINE.

1,144,944.

Specification of Letters Patent. Patented June 29, 1915.

Original application filed August 17, 1910, Serial No. 577,616. Divided and this application filed January 3, 1911, Serial No. 600,382. Renewed December 16, 1914. Serial No. 877,612.

To all whom it may concern:

Be it known that I, FRANCIS MEISEL, a citizen of the United States, residing at Boston, in the county of Suffolk and State 5 of Massachusetts, have invented a new and useful Printing-Machine, of which the following is a specification.

This invention relates to a printing machine and this application is a division of 10 my patent on a printing and numbering machine, filed Aug. 17, 1910, patented August 6, 1912, No. 1,034,637.

The principal objects of the invention are 15 to provide an improved way of setting up and supporting the mill rolls of paper to be fed into the machine, and an improved combination thereof with feed roll guides, and collating device, and to provide an improved collating device.

20 The invention also involves improvements in details of construction and combinations of parts as will appear hereinafter.

Reference is to be had to the accompanying drawings in which—

25 Figure 1 is a diagrammatic side elevation of a printing machine constructed in accordance with this invention, and Fig. 2 is a plan of a collating device.

In the form of the invention shown in the 30 drawings the main frame 10 of the machine is connected by links 11 or the like with a base or stand 12 for a plurality of sets of brackets 13 adapted to support the paper rolls. This machine being designed particularly for printing a plurality of webs at 35 the same time, these rolls are arranged so that a number of them can be placed on the machine at once to feed the webs through simultaneously. In the present case each of

40 the brackets 13 is of a general triangular shape and is supported on planing spots 130 on the frame and bolted to the frame at the rear so as to extend forwardly therefrom to have a bearing well forward of the bolts.

45 The bolts are located substantially under the centers of the bearings at the top of the brackets. In this way it will be seen that any force applied to the webs pulling toward the main frame 10 will serve to keep the

50 brackets seated firmly on the base and held securely in position. Each of the brackets is provided with a swinging member 14 having a half bearing for the shaft of the roll and a swinging locking member 15

therefor. In the present instance four webs 55 a, b, c, and d, are shown but it will be understood that any other number of webs can be passed through the machine. The webs all pass to a positively driven lower feed roll 20 which extends across the machine and 60 takes in all the webs, and under which they extend and then pass upwardly over a positively driven upper feed roll 22. From this roll the webs fall and each forms a loop in which is located a light roller 23. This prevents entanglement of the web during its rapid passage through the machine. Each web then passes under and over stationary bars 24, 25 and 26. On the bars 24 and 25 are laterally adjustable guides 28 between 65 70 which the webs pass. Thus the webs are guided laterally and kept in proper relative position so that they can be cross associated as explained hereinafter with the printed matter in registration. The irregularity in 75 the edges of the rolls renders this guiding necessary. It will be understood that the feed rolls 20, 22 and 27 are similar and the latter are positively driven by a gear 30 operated by mechanism which it is not necessary to describe in detail as it is well understood in this art. The webs then pass 80 over individual feed rolls 31—32 through the printing mechanism which is designated in a general way by the letter P and the 85 details of which will not be described, as any printing mechanism can be employed. The webs then pass to a numbering mechanism N. After the plurality of webs have passed through the numbering mechanism they are 90 brought through a collating device to which they pass from between rolls 98. The drawings show four webs, each passing to a different roll 100, 101, 102 and 103 located at different points in order to register with the 95 proper part of the collating or registering device. The purpose of the collating device as will be understood is to bring these four or other number of webs into registration 100 with each other, one over the other, so that when they pass between rolls 104 to be taken to the cutter or other mechanism they will be in perfect registration. For this purpose the frame of the machine is provided with bearings in which are located the journals 105 for the rolls 100, 101, 102 and 103 and on which also are located frames 106, 107 and 108. Under the bottom frame the under

web *a* passes from the roll 100 to another roll 110 without deviation from its course. The other three webs are intended to be brought from their positions at the side of this web *a* and carried directly over it so that they issue from the collating device in registration with it.

The web *b* travels to an intermediate position under the roller 101 and is brought 10 out from the machine under a roll 111. For this purpose the lower frame 108 is provided with two fixed turning bars 114 located at an angle of 45 degrees to the direction of motion of the web and parallel with 15 each other. These bars are spaced far enough apart so that the web *b* enters the collating device over them and over the frame 108, then passes around the outer bar and down under it so as to take up 20 a direction transverse to the direction of motion of the web *a*, then passes around the other bar 114 and out of the collating device directly over the web *a* to the delivery roll 111. The web *c* which passes under 25 the roll 102 on one end comes over a turning bar 115 on the frame 107, then under it and under another turning bar 115 on the same frame and out over the other two webs to the delivery roll 112. These turning 30 bars 115 are located at an angle of 45 degrees to the direction of travel of the web, and one of them is directly over the inner turning bar 114 but they are farther apart than the bars 114. The web *d* comes 35 in from the roll 103 over the upper frame 106 and its turning bars 116, around which it passes to the delivery roll 113. The turning bars 116 are at an angle of 90 degrees to the other turning bars. It will be 40 understood, of course, that with a greater number of webs pairs of turning bars of the same character parallel with those described will be provided, but if the other webs entering the collating device are at 45 a greater distance from the top web their turning bars will simply be a greater distance apart. In all cases the delivery turning bars of all pairs are directly under or over the inner bars of the pairs described. In this way it will be seen that 50 the several webs, of the same or different colors, are printed while being taken through the machine parallel with each

other and all in the same plane, and that they are then collated and registered so 55 that they issue one over the other.

While I have illustrated and described a preferred embodiment of the invention, I am aware that many modifications can be made therein by any person skilled in the 60 art without departing from the scope of the invention as expressed in the claims. Therefore, I do not wish to be limited to all the details of construction herein shown and described, but 65

What I do claim is:—

1. The combination with a frame, of a plurality of mill rolls mounted side by side at the end of said frame, a positively driven feed roll extending across the frame and 70 receiving the webs from all of said mill rolls, a set of feed rolls, one for each mill roll for receiving the several webs from the first named feed roll, and means for feeding each of said webs separately from the 75 feed rolls and registering them with each other.

2. The combination with a frame, of a plurality of mill rolls mounted side by side, a positively driven lower feed roll extending 80 across the frame and receiving the webs from all said mill rolls, an upper feed roll, for receiving the several webs from the first named feed roll, a series of lateral guides for each web, feed rolls beyond said 85 guides for receiving each of the webs, and means for feeding the webs individually from the second set of feed rolls.

3. The combination with a frame, of a plurality of mill rolls mounted side by side 90 at the end of said frame, a positively driven feed roll extending across the frame and receiving the webs from all the said mill rolls, a set of feed rolls, one for each mill roll, for receiving the several webs from 95 the first named feed rolls, means for feeding each of said webs separately from said set of feed rolls, and means for bringing the several webs into register.

In testimony whereof I have hereunto set 100 my hand, in the presence of two subscribing witnesses.

FRANCIS MEISEL.
